UNITED STATES PATENT OFFICE.

FREDERICK A. NIXON, OF EASTON, PENNSYLVANIA.

TRAIN-CONTROLLING SYSTEM.

Application filed March 17, 1926. Serial No. 95,196.

This invention relates to electrically operated train controlling systems of the type embodying a conductor running contiguous to the track rails and divided into sections 5 corresponding to block lengths.

More specifically this application is directed to the disclosure of my prior—but now abandoned—case filed the 4th day of August, 1922, under Serial Number 579,556, 10 and it has for an object to provide an improved train controlling system which is characterized by the provision of means in each block for generating a "pseudo-alternating current"; or, more correctly what is 15 termed a "reversing pulsating current", for impressing the current upon the conductor at varying frequencies: and a locomotive equipment for coordination with the throttle and air brakes of a train and responsive to 20 such pseudo-alternating current—and frequency variations therein—to effect control of the speed of said train in any block with respect to that of a preceding or following train and to effect a complete stop of any 25 train, without requiring the attention of the engineer and—in a manner—entirely independent of his control.

In addition to the foregoing this invention comprehends improvements in the details of 30 construction and arrangement of the correlated parts of what I now regard as the preferred embodiment of my invention from among many other possible forms and arrangements thereof, within the spirit of said 35 invention, and which is hereinafter set forth and particularly pointed out in the appended claims.

In the accompanying drawings:

Figure I, is a diagrammatic view in plan 40 of three block sections embodying my improved train controlling system, and illustrating the relative positions of corresponding parts in the respective block sections with their electrical connections to the track 45 rails and conductor.

Figure II, is a view in front elevation of a 50 commutator forming part of a frequency controller or current converter used in connection with the present invention.

Figure III, is a view of the commutator

and correlated parts in longitudinal section.

Figure IV, is a diagrammatic view illustrating the elements and their connections forming the locomotive equipment of the present invention.

Figure V, is a diagrammatic view in side elevation of a mechanical device, operated electrically, for releasing the throttle valve; and,

Figure VI, is a detail view—in section—of 60 an air valve and its electrical operating means.

With reference to Figure I of the drawings, 10 indicates the track rails and 11 a conductor, located between said rails and 65 running in contiguous relation thereto throughout the length of the track, said conductor being divided into live sections 12 located between the sections of a block signaling system, and subdivided into stopping sections 13, one of which is located between each adjacent end of an adjoining pair of live sections 12 and only of sufficient length to stop a train running at "caution" speed. The sections 13, while normally energized 70 are termed stopping sections as they function to arrest motion of the train when de-energized, while the sections 12 are constantly energized. To illustrate the relation of corresponding parts in each of the block 75 sections under varying conditions I have shown diagrammatically the necessary elements and wiring connections conventionally indicated in the drawing at A, B and C, as well as the semaphore signal of each section, the lower or "distant" semaphore arm being indicated at 15 and the upper or "home" semaphore arm at 16. Each block 80 section equipment includes a current converter or frequency controller shown in detail in Figures II and III, wherein 17 indicates generally a commutator or rotary reversing switch comprising a disk of insulating material and having concentrically applied to its face a pair of collector rings 18 85 and 19, and two annular series 20 and 21 of spaced segments, the segments whereof are arranged in radial alignment. Each segment of the inner series 20 is connected by 90 means of concealed conductors 22 with the 95

Figure II, is a view in front elevation of a 100 commutator forming part of a frequency controller or current converter used in connection with the present invention.

two flanking misaligned segments of the outer series 21, and each segment of said outer series 21 is similarly connected at each end by means of concealed conductors 23 5 with a pair of misaligned flanking segments of the inner series 20.

A concealed conductor 18' connects the collector ring 18 with one of the segments in the inner segmental ring 20, while a similar 10 conductor 19' connects the collector ring 19 to another unit of said segmental ring 20; and it is noteworthy, at this juncture, that the insulated intervals between the segments comprising the rings 20, 21 must be of sufficient "gap" so that a direct current arc of requisite voltage and amperage will not flow or "jump" from segment to segment when the required velocity is attained. The 15 commutator or frequency controller 17 is mounted for rotation upon a shaft 24, having a collar 25 formed therewith against which the disk bears in tight engagement brought about by pressure of a nut 26 threaded upon said shaft engaging a collar 27 which contacts with the rear face of said disk. The shaft 24 is journaled in bearings 28 and may be provided with a pulley 29, for imparting rotative movement thereto; or, if desired, said shaft may be 20 directly coupled to the shaft of a suitable motor. A pair of spring pressed brushes 30 and 31 are provided, engaging respectively the inner and outer collector rings 18 and 19; and, in similar manner, a pair of brushes 32 and 33 are arranged to wipe the face of the commutator disk in radial alignment, so as to respectively engage the segments of the annular series 20 and 21 during rotation of the disk. The commutator 17 is 25 driven by means of a direct current motor 34, which is fed through the lead 35 directly connected thereto, and by means of a lead 36—which extends to the brush 31—that is provided with a branch conductor 37 extending 30 to the movable contact of a variable resistance element 38. A branch 39 is taken from the lead 35 and extended to the brush 30. It will, of course, be readily understood by those acquainted with the art that 35 the direct current—"input"—fed to the brushes 30, 31 will produce an alternating current—"output"—at the brushes 32, 33 when the commutator 17 revolves. The brushes 32 and 33 are connected by means of 40 conductors 40 and 41—respectively—to a live section 12 of the conductor 11 and to one of the track rails 10. The variable resistance element 38 is in series with a fixed resistance element 42, which in turn is disposed in series with the movable conductor of a second variable resistance element 43, in turn connected through the medium of a conductor 44 to a contact point 45, forming 45 part of a switch 51 designed to be operated by and in unison with the lower arm 15 or

"distant" semaphore, in any of the well-known ways, or as indicated by the dotted lead lines connecting said parts. The switch 51 includes a switch arm 56 adapted to oscillate between the contact 45 and an adjoining contact 58. The switch arm 56 is connected by means of a conductor 49 to the juncture of the variable resistance 38 and the fixed resistance 42, as shown in the drawing. Associated with the "home" 55 semaphore arm 16 is a switch 50, said switch 50 comprising an arm 52 operative by and in unison with said semaphore arm 16, as before described in reference to the arm 15; and that it is connected by means of a conductor 53 to the live section 12 of a preceding block—considered with reference to the direction of travel of the train, and a contact 54 which is connected by means of a lead 55 to the adjacent stopping section 13. 60 It is here noteworthy that the switches 50 and 51, with their associated contacts, are in addition to the usual contacts and are operated by the signal or semaphore movements. 65

It will be apparent that since the main leads 35 and 36 are in constant electrical communication with one of the rails 10 and conductor 12 through the intermediary of the commutator 17 a constant potential will 70 be impressed upon the live rail 10 and conductor 12, and the circuit will be completed by passage of the current through the car wheels and axles of a passing train. Owing to the provision of the commutator 17 a 75 direct current fed from the leads 35 and 36 is converted into what, for the want of a better term, may be called an alternating current, although differing therefrom in several particulars, as for instance the absence of a 80 sine curve characteristic, the current flowing in a series of impulses which are constantly reversing and which begin and end with a maximum electromotive force. This is occasioned by reason of the segments of the 85 series 20 and 21 being misalignedly connected, or one to the other alternately as described above, so that the collector brushes 32 and 33, being stationary and in radial alignment, connect alternately during rotation of the commutator 17 with the inner and outer segments of the two series 20, 21, thereby 90 constantly reversing the current at a rate of reversal or frequency determined by the speed of rotation of the commutator 17. 95 The change in speed of rotation of the motor 34, and hence the frequency of the converted current is obtained by manipulation of the semaphore arms 15 and 16, communicated in turn to the switches 50 and 51, by which the 100 interposition of the resistance controlling said motor is accomplished. For instance, observing the relation of the parts at signalling location A which are set to indicate a 105 clear track and to permit passage of a train 110

into the block controlled thereby without diminution of speed, the switch 51 is in a position so that the arm 56 engages the contact 45, thereby establishing a circuit which 5 includes the leads 36 and 37, resistance 38, conductor 49, switch arm 56, conductor 44, and conductor 60 which connects the latter with a terminal of the motor 34, the current returning therefrom through the lead 35. 10 Since this circuit includes only the single resistance 38, the motor 34 is permitted to rotate at its maximum speed, and hence the converted current will be fed to the rail 10 and conductor 12 at a maximum frequency 15 which acts upon the mechanism of a locomotive equipment responsive thereto to permit the train to move without diminution of speed. At this point it is to be noted that a train entering any block controlled by my 20 novel system first encounters the portion 12 of the conductor 11, before rolling onto the minor portion 13; or, in other words said portion 13 is located adjacent the exit end of each block.

25 The signaling mechanism shown at B is for the purpose of illustrating "caution" conditions or as effected by diminution of speed—incident to inclusion in the circuit described in the preceding paragraph of the fixed resistance 42—of the train entering the block controlled thereby.

To further illustrate the operation of the mechanism the parts at C have been shown as set to indicate a "danger" or stop position for the block controlled thereby or when 30 both semaphore arms 15 and 16 are elevated which results in the shifting of both switch arms of the switches 50 and 51 to the open positions. In this position of the parts the motor 34 is permitted to run only at a further reduced rate of speed owing to the fact that the current now traverses all of the resistances 38, 42 and 43. The converted current under such conditions affects the mechanism of an approaching locomotive in the 35 block controlled thereby, before the "danger" zone can be reached, inasmuch as the locomotive must traverse a section 13 which, in the present instance, is de-energized by reason of the opening of the switch 52, and 40 as soon as the locomotive passes beyond the live section 12 of the preceding conductor rail section 12 and rolls onto said de-energized section 13, the mechanism of the locomotive equipment—being thereby de-energized—is instantly actuated to apply the air 45 brakes and cause the train to come to an abrupt stop before its inertia carries it beyond said section 13.

Briefly summarizing, and assuming the 50 signal indications are as shown, a train entering a block controlled by signal indications A—or "line clear"—traverses the live rail section 12 of said block, which is supplied with current of full speed frequency 55 by virtue of the resistances 42, 43 being shunted by the switch 56; while the rail section 13 immediately ahead receives current of the same frequency through the switch 52. When a train enters a block under control of signal indications B or—"caution"— 60 the rail section 12 therein receives somewhat reduced frequency current, so that "caution" speed conditions exist up to the exit from said block section. Should the train enter a block under C signal indications, 65 after passing the "caution" or B controlled block, the switch 56 being open permits both the resistances 42 and 43 to become operative to reduce the speed of the corresponding motor 34, so that current at a considerably 70 reduced frequency is fed to the rail section 12 under control of C, while the rail section 13 in said block receives no current at all, or is totally de-energized, due to the switch 52 now being open, and as a result the train 75 is automatically brought to a "dead" stop before it can pass the exit of the block under control of C signalling indications.

While the switches 50 and 51 may be controlled manually or by operation of the 80 semaphore arms, it will be apparent that, if desired, the system may be rendered fully automatic by providing means of a simple character adapted to be actuated by a passing locomotive to set said switches in a 85 block in advance of the approaching locomotive.

The locomotive equipment to be used in connection with the controlling system described may be of an extremely simple character, and—as one example—I have illustrated a means in Figures IV, V, and VI, 100 adapted to perform the intended functions. In these views, 61 indicates a locomotive axle upon which a bevel gear 62 is fixed for rotative engagement with a gear 63, in turn mounted upon a governor shaft 64, which carries a centrifugal governor mechanism 64^a adapted upon rotation to impart motion to a rock lever 65. This lever 65 is suitably 105 supported and adapted to actuate—through the medium of a link 66—a bell crank 67, in turn connected by means of a link 68 to one movable member of a contact making device 69. This contact making device 69 110 comprises a series of spring influenced pivotal contacts 70, 71 and 72, which are adapted to be successively picked-up and engaged by a pivoted contact arm 73, movable also with respect to the movable contacts 70, 71 115 and 72. The contact arm 73 is connected to a link 74 made extensible by having a spring 75 interposed therein, said link 74 being connected to one arm of a bell crank 76, the other arm of which is connected by 120 means of a link 77 to a rock lever 78. The lever 78 is oscillated through the medium of a centrifugal governor mechanism 79, which is operated by means of a bevel gear combination 80, 81, said latter gear 81 being ro-

125

130

tated by means of a split phase motor 82, one terminal of which is grounded to the engine and the other connected to a shoe 83 adapted to travel along the conductor 11 between the track rails 10, 10. The locomotive equipment also includes three relays 84, 85 and 86 adapted to be energized by current supplied from a source 87 and controlled by connections to the contacts 70, 71 and 72—respectively—of the movable contact maker 69. The relay 84 controls the energization, through the wiring illustrated, of an electromagnet 88, forming part of a mechanism for accomplishing the release of the throttle and which is shown in Figure V. The throttle valve, indicated at 89 is actuated by means of a link 90, carrying a pivoted hook member 91, which normally is interengaged with a similar hook member 92 actuatable by the throttle lever 93. As long as the members 91 and 92 are in mutual engagement the steam throttle may be opened and closed by shifting the throttle lever 93, in the usual manner. The hook member 91 however, is normally urged to a position tending to release the member 92 by virtue of a spring 94; but, contrarily, said hook member 91 is urged towards engaging position by means of a core 95 which, under the influence of the energized electromagnet 88 tends to retain the hook member 91 in engagement with the hook member 92 by overbalancing the tension of the spring 94. It is well to note that the throttle valve 89 being only partially balanced will automatically close on disengagement of the members 91, 92. Thus it will be clearly seen that the throttle lever 93 would become ineffective until returned to latched engagement with the member 91.

The locomotive equipment also includes means for venting the brake pipe to secure an application of the brakes. To this end a valve, illustrated in Figure VI, is provided and connected to the brake pipe, the valve indicated at 96 being actuated through the medium of a stem 97, having its terminal extended to provide a core 98, which operates axially through two electromagnets 99 and 100. The valve 96 is normally urged to open position by means of a spring 101 interposed between the valve casing and an adjustable abutment 102, threadedly engaged upon the valve stem 97, said valve 96 being held in closed position against the influence of the spring 101 by the energization, singly or in unison, of the electromagnets 99 and 100. To balance movement of the valve 96 so as to ensure a positive and free brake application, I may append a piston 103 thereto operating in a cavity 104 in the valve casing which is placed in communication with the atmosphere by means of a restricted aperture or vent 105.

In the operation of the locomotive equip-

ment, assuming that the engine is traveling at a maximum rate of speed the contact members 69 and 73 will be shifted towards each other, in an obvious manner, by rapid rotation of their respective governor mechanisms to extreme advanced positions, whereupon all the three contacts 70, 71 and 72 will be successively interengaged with the member 73 contacting the member 72, so as to effect and maintain energization of the associated relays 84, 85 and 86. Thus it will be clear, that, the electromagnet 88 being energized through the normally closed position of its corresponding relay 84 retains the hook members 91 and 92 in mutually engaged position, permitting adjustment of the throttle to vary the admission of steam in the usual manner. The electromagnets 99 and 100 being likewise energized function to retain the valve 96 in closed position. Should the train enter a block controlled by the signal set to "caution," as for instance shown at B in Figure 1, and the engineer has not reduced speed, the motor 82 of the locomotive equipment will be automatically supplied with a current of a lesser frequency, and as a result thereof its speed of rotation is reduced. The first result of such automatic reduction of speed of the motor 82 is to cause diminution in the speed of rotation of the associated governor mechanism 79, which in turn effects retraction of the contact member 73 to a position wherein the contact 70 is released, but retaining engagement with the contacts 71 and 72. As a consequence the relay 84 is de-energized in turn causing de-energization of the electromagnet 88, which effects release of the hook member 91, under the tension of the spring 94 thereby causing the throttle valve 89 to automatically move to closed position and shut off steam from the locomotive cylinders. Should the train however proceed until it approaches the end of the block controlled by signal setting B, with the signal in the block approached set against it, as shown by C, resulting in the formation of a dead section 13, the supply of alternating current to the motor 82 will be automatically discontinued, thus effecting retraction of the contact 73 beyond the contact 71, de-energizing the relay 86 and its associated electromagnet 99, so that the valve 96 of the brake pipe vent will be shifted under the influence of the spring 101 against the retarding influence of the still energized electromagnet 100 to a position where the brake pipe is slowly vented to effect a service application of the brakes. On the other hand, if the engineer has properly reduced speed to conform with track side conditions it will be seen that with the foregoing position of the parts, should the locomotive, for any reason pick up speed, even during the service applica-

tion of the brakes, as for instance by proceeding onto a down grade, such increase in speed will be imparted through the governor mechanism 65 to effect still further retraction of the contact member 69 to the left, resulting in disengagement between the contact 72 and the contact 73. This act results in the de-energization of the relay 86 and its associated electromagnet 100, thereby permitting the spring 101 to act with full force to move the valve 96 to a full open position quickly venting the brake pipe and causing an emergency application of the brakes. In this manner the speed of the locomotive and the speed of the motor 82 are permitted to act as a check, one upon each other, thereby effecting complete control of the locomotive at any predetermined speed of said motor 82, irrespective of external conditions acting upon the locomotive to advance or retard its speed. Other advantages result from the arrangement described, as for instance, complete control of the speed of the locomotive independent of the control of the engineer, so that the predetermined rates of speed fixed by law may not be exceeded—or the train subjected to unwarranted risks—by negligence of the engineer. Owing to the fact that during normal operation the system is constantly energized throughout on closed circuits, any derangement of the mechanism tending to cause a break in the circuits would act to effect a reduction in speed—or stoppage—of the locomotive, thus increasing the factor of safety. Other advantages will be readily apparent to those familiar with the art to which this invention relates. It has been found by experiment that a split-phase motor—such as 82—on the locomotive will operate efficiently on the type of converted current mentioned above, although the split-phase winding must be specially designed to withstand continuous connection to the source of current. In lieu of the particular form of current converter described I may employ an ordinary direct coupled motor-generator set to furnish an alternating current. It is understood that the term "locomotive" as used herein may include also an electric locomotive or other tractive vehicle; and that "throttle" is the equivalent of a controller or any device for controlling the speed of the vehicle. Also, in place of the centrifugal governors 64^a and 79 I may use any other suitable form of speed responsive mechanism, while I have proven by actual service tests that all changes in the speed of the frequency controller or current converter 17, gave a proportional change to the speed of the split-phase induction motor 82 when direct current was supplied to said frequency controller.

From the foregoing description and an examination of the drawings it will be obvi-

ous to anyone conversant with the art that my invention is based upon the fundamental principle that variation in the frequency of an alternating electromotive force insures a corresponding variation in the speed of an induction motor connected thereto.

Having thus described my invention, I claim:

1. In a train controlling system, including a track equipment having a conductor paralleling the tracks divided into sections, locomotive equipment including means responsive to an alternating current received through the conductor sections in passing thereover to effect control in the speed of the locomotive, and a series of trackside equipments, one for each conductor section and each including means for generating—and impressing a pseudo-alternating current upon its corresponding section, means for controlling the frequency of the current impressed with respect to successive track equipments so as to effect reduction in speed of a train passing from one section to another by reduction of the frequency of the current impressed upon the section approached, a de-energizable section interposed in each of the aforementioned conductor sections, and means controlling said de-energizable or dead section, whereby the locomotive equipment is rendered responsive in passing over such dead section to effect a complete stop of the locomotive.

2. In a train controlling block system, a track equipment including a conductor paralleling the tracks, said conductor being divided into live sections with a stopping or de-energizable section for each block, a locomotive equipment including means responsive to an alternating current received from the conductor sections to effect control of the speed of the locomotive, and a track equipment including a plurality of signal stations, one for each conductor section to impress a pseudo-alternating current thereupon and to vary the frequency of the current impressed to effect control of the speed of the locomotive, and means for connecting and disconnecting each stopping section with an associated live conductor section to permit control of the locomotive in passing over a stopping section when the latter is energized, and to effect a responsive action of the locomotive equipment when passing over such stopping section when the latter is de-energized to automatically effect stoppage of the locomotive.

3. In a train controlling system, including a locomotive equipment having means responsive to an alternating current to effect a secondary control of the speed of the locomotive, a track side equipment including a current converter for converting a direct current into an alternating current and for impressing the same upon the responsive

means of the traveling locomotive, and means for varying the speed of the converter to vary the frequency of the current impressed.

5 4. In a train controlling system, a locomotive equipment including means responsive to an alternating current of varying frequency to effect a secondary control of the speed of the locomotive, a track side 10 equipment including a motor operated converter for converting a direct current into an alternating current and for impressing the same upon the responsive means, resistance elements adapted to be interposed in 15 circuit with the motor to effect changes in speed, and means for controlling the interposition of the resistance elements.

5. In a train controlling system, the combination in a locomotive with the throttle 20 and brake valve, of a split-phase motor for receiving alternating current of variable frequency from an external source, means operable by initial reduction in speed of the motor to close the throttle, and means operable by a secondary reduction in speed of the 25 motor to actuate the brake valve to effect an application of the brakes.

6. In a train controlling system, a locomotive equipment including a split-phase motor 30 to receive alternating current from an external source, a multicontact circuit maker, means controlled by the circuit maker to actuate controlling devices of the locomotive, and means controllable by changes in 35 speed of the locomotive acting upon the circuit maker in opposition to the controlling effect of the motor to effect adjustment of the circuit maker to positions reverse to those effected by the motor, for the purpose set forth.

7. In a train controlling system, a locomotive equipment including a split-phase motor responsive to alternating current received from an exterior controlling source, a 45 governor mechanism operable by the motor, a circuit controller operable by the governor mechanism, a second governor mechanism operatively connected to the wheels of the locomotive to effect adjustive relation 50 of the circuit controller to positions reverse to those effected by the first governor mechanism, and means operable by the circuit controller to actuate the locomotive controlling devices.

8. In a train controlling device, the combination in a locomotive of a throttle valve having a separable operating device, means urging the operating device to separation 60 to permit release of the throttle valve, and normally energized means retaining the device in interengaged relation, and means responsive to exterior control to de-energize the retaining means for the purpose set forth.

In testimony whereof, I have hereunto signed my name at Easton, Pennsylvania, this 13th day of March, 1926.
